United States Patent Office.

JOHN MCNEVEN, OF NEW YORK, N. Y.

Letters Patent No. 96,940, dated November 16, 1869.

IMPROVEMENT IN VAPOR-BATH APPARATUS.

The Schedule referred to in these Letters Patent and making part of the same

To all whom it may concern:

Be it known that I, JOHN MCNEVEN, of the city, county, and State of New York, have invented a new and improved Bathing-Apparatus; and I do hereby declare the following to be a full, clear, and exact description thereof, which will enable those skilled in the art to make and use the same, reference being had to the accompanying drawing, forming part of this specification, in which drawing.

Figure 1 represents a longitudinal vertical section of this invention.

Figure 2 is a transverse vertical section of the same.

Similar letters indicate corresponding parts.

This invention consists, among other things, in the arrangement of a series of boilers in the base-plate of a bathing-apparatus, in combination with a perforated dripping-plate, which covers the boilers, and forms the support for the person using the apparatus, in such a manner that by filling the boilers with water or other fluid, and heating the same, the person enclosed in the apparatus is soon enveloped in a volume of steam, while the dripping-plate protects the feet or other parts of the body of said person against the direct action of the heat, and serves to carry the water resulting from the condensation of the steam, back into the pan underneath.

The water in the boiler or boilers is heated by gas or other flames, fed with the requisite burning material, through pipes situated in the interior of the bathing-apparatus, and provided with stop-cocks, so that the person enclosed in the apparatus can heat either or all of the boilers, as may be desirable.

A hinged partition-plate, in the upper part of the apparatus when let down, serves to prevent the steam or heated air from escaping in a direct course through the top of the apparatus, and if said partition-plate is turned up, and an aperture in the lower part of the apparatus is opened, a current of cold air passes through the apparatus and cools the same and its occupant off in a short time.

A condenser, secured in the top of the apparatus, prevents the escape of steam into the room, and with this condenser is combined a vessel, supported by trunnions, which, when filled with water, can be emptied by pulling a cord, so that the person occupying the apparatus can have a shower-bath whenever it may be desirable.

In the drawing, the letter A designates a case made of wood, or any other suitable material, and large enough to admit one or more grown persons.

A door, B, gives admission to said case, and this door can be fastened by any suitable device.

In practice, the door will be provided with panes

of glass, so that the light has free access to the interior of the case when the door is closed.

In the bottom part of the case A is secured a metal pan, C, which is perforated with a series of holes, to receive the boilers D, and over the metal pan extends the base-plate E, which is hinged to the case, and provided with ribs a on its lower surface, so that said base-plate, when turned down to its working position, will be kept at a certain elevation above the boilers D, as shown in the drawing.

This base-plate serves as the bottom for the person occupying the case A to stand upon, and it is slightly curved upward, and provided with a number of small holes, b, so that the water resulting from the condensation of steam in the apparatus, has a chance to find its way down into the pan C.

The boilers D are intended to be filled with water or other fluid, which is heated by flames c, supplied with gas or other burning-material, through pipes d d.

These pipes branch off from a common supply-pipe, e, and they are situated in the interior of the case A, and provided with stop-cocks f, so that the person occupying the case is enabled to regulate the heat under the several receivers, to suit convenience.

The steam rising from the fluid in the boiler or boilers, passes up through the perforations b, in the base-plate E, and comes in contact with the body of the person enclosed in said case, and the water resulting from the condensation of the steam runs back into the pan C.

To the inner sides of the case A are secured the chairs F, the seats of which are perforated, and made of sheet-metal, or other suitable material, and which are so arranged that they can be turned up or down.

In the upper part of the case A is the partition-plate G, which is made of metal or other suitable material, hinged to the sides of the case A, near its back, so that it can be raised by means of a rope, g, which extends from the front edge of the said partition-plate through an eye-bolt or staple, h, down into the bathing compartment of the case A, so that the person occupying said compartment can readily raise or lower the partition-plate.

If the partition-plate is down, it confines the heat in the bathing compartment, but if said plate is raised, a current of air may be passed through the case A, for the purpose of cooling.

To effect this object, an aperture, i, is cut into the sides of the case A, close over the base-plate, and this aperture is to be furnished with a door or cover, so that it can be opened or closed at convenience.

The top of the case A is perforated with a large aperture, j, either square, round, or of any other de-

sirable form or shape, and in this aperture is secured a vessel, *k*, made of sheet-metal, or any other suitable material, and in this vessel is secured a second vessel, *l*, which swings on gudgeons *m*, and is intended to be filled with cold water.

In the bottom of the outer vessel *k*, is a hole, *m'*, through which the steam from the case *A* exhausts, and as this steam comes in contact with the cold sides of the inner vessel *l*, it condenses, and is thus prevented from filling the room.

From the inner vessel *l* extends a cord, down into the case *A*, so that the person occupying said case, by pulling said cord, can empty the water contained in the vessel *l*, and thus take a shower-bath whenever it may be desirable.

If a hot-air bath is desired instead of a steam-bath, the boilers *D* are removed, and the openings in the pan *C* are closed by suitable covers, and, by heating said pan, the air in the case *A* can be readily brought to the desired temperature.

While taking the bath, the mouth or the nose, or both, may be protected by fresh air-caps *n*, from which extend pipes, through openings in the sides of the case,

so that the person enclosed in said case is supplied with fresh air for breathing.

Having thus described my invention,

What I claim as new, and desire to secure by Letters Patent, is—

1. The perforated base-plate *E*, in combination with case *A*, and with the pan *C* and the boiler or boilers *D*, substantially as described.

2. The pipes *d d e*, provided with stop-cocks *f*, in the interior of the case *A*, in combination with the pan *C* and base-plate *E*, and boiler or boilers *D*, substantially as set forth.

3. The arrangement of the hinged partition-plate *G*, between the steaming or heating-apparatus, at the base of the case *A*, and the exhaust at the top thereof, substantially as and for the purpose described.

4. The combination of the swinging interior vessel *l*, the outer vessel *k*, provided with exhaust-port *m'*, and the case *A*, substantially as set forth.

JOHN McNEVEN.
